CLAIM

The ornamental design for a tattoo pen, as shown and described.

DESCRIPTION

FIG. 1 is a top perspective view of the wireless power supply tattoo pen (HP02) showing my new design.

FIG. 2 is a front view of the wireless power supply tattoo pen (HP02).

FIG. 3 is a rear view of the wireless power supply tattoo pen (HP02).

FIG. 4 is a left side view of the wireless power supply tattoo pen (HP02).

FIG. 5 is a right side view of the wireless power supply tattoo pen (HP02).

FIG. 6 is a top view of the wireless power supply tattoo pen (HP02).

FIG. 7 is a bottom view of the wireless power supply tattoo pen (HP02).

FIG. 8 is a bottom perspective view of the wireless power supply tattoo pen (HP02).

FIG. 9 is an enlarged view of FIG. 1.

FIG. 10 is an enlarged view of FIG. 6; and,

FIG. 11 is an enlarged view of FIG. 7.

The broken lines depict portions of the tattoo pen that form no part of the claimed design.

1 Claim, 11 Drawing Sheets
